UNITED STATES PATENT OFFICE.

HENRY S. HOLMES, OF NEW YORK, N. Y., ASSIGNOR TO THOMAS E. MURRAY, OF BROOKLYN, NEW YORK.

STAMPING APPARATUS AND PROCESS.

Application filed March 21, 1921. Serial No. 453,916.

To all whom it may concern:

Be it known that I, HENRY S. HOLMES, a citizen of the United States, and resident of New York city, New York, have invented 5 certain new and useful Improvements in Stamping Apparatus and Processes, of which the following is a specification.

The invention aims to provide a quick and economical process of shaping articles 10 of sheet metal.

The accompanying drawings illustrate an embodiment of the invention.

Fig. 1 is a vertical longitudinal section of a lower die with a blank and an upper die in 15 elevation, showing the position of the parts before the operation;

Fig. 2 is a plan of the lower die with the finished article therein;

Fig. 3 is a plan of the blank with a side 20 elevation in juxtaposition thereto;

Fig. 4 is a side elevation of the blank in an intermediate stage of the operation;

Fig. 5 is a longitudinal section of the finished article;

25 Figs. 6 and 7 are cross-sections of the upper and lower dies respectively on the lines indicated in Fig. 1; the finished article being illustrated in connection with Fig. 7.

Referring to the embodiment of the invention illustrated, the article to be produced is one-half of a rear axle housing for automobiles, divided along a longitudinal plane. It is illustrated as a whole by the numeral 1 and in cross-section shows a bottom 2 and sides 3 extending upward therefrom at right angles, with straight upper edges 4 and a circular portion cut away at the center as at 5. The bottom is flared downward or outward at the ends 6 and has a depressed central portion 7 concentric substantially with the curved edge 5 of the flanges. The article is made from a blank 8, Fig. 3. It is first bent in longitudinal section to the shape shown at 9, Fig. 4, its horizontal section remaining flat. In the continued operation of the machine it is bent in transverse section to fold up the sides 3. Each of these operations is chiefly or largely a bending or folding operation 50 with the edges of the blank free as distinguished from the ordinary drawing operation in which the edges of the blank are held strongly between clamps from which they are gradually drawn by the pressure at the center. There is little or no draw-

ing of the metal, the actual amount of drawing depending more or less on the shape being produced. By using an operation which is chiefly or solely bending, the product can be obtained with a much smaller expenditure of power and time than is necessary in the complete drawing operations which have generally been employed for producing such shapes, and a very much simpler and lighter machine may be used for the purpose. Furthermore, with this method the metal is not thinned out to any great extent, as in the ordinary drawing operation which produces a considerable variation in the thickness of the product. The product of my process is uniform even when using metals of different drawing qualities, and in fact it is not necessary to use the same expensive quality of metal which is required to withstand a drawing operation.

To secure the bending operation described the die 10 has its sides 11 shaped on their upper edges 12 to the longitudinal contour of the blank, and the punch 13 has its working face 14 similarly shaped. The bottom 15 of the die is similarly shaped. The first effect of the operation, when the punch is pressed toward the die, will be to bend the flat blank 8 in longitudinal section to the shape of the edges 12 and the working face 14 of the die and punch, that is to the shape of Fig. 4. The working face 14 of the punch does not extend clear across the width of the blank, as will be seen from Figs. 6 and 7, where the blank 8 is illustrated in dotted lines. But the effect will be to press the engaged parts of the blank down across its entire width until the edges come to be supported on the edges of the die. When this position is reached throughout the length of the blank we have what may be called the end of the first stage of the process; although it will be understood that the movement of the punch may be uninterrupted. Thus the product may be turned out much more rapidly than where the operation is interrupted after the first stage in order to reset the machine for the second stage or to transfer the blank to another apparatus for the second stage.

As the punch continues downward, being shaped to fit into the recess in the die, with only the necessary clearance at the sides, it will bend up the two longitudinal sides 3 of the product and will force them out

horizontally to fit the inner face 16 (Fig. 2) of the sides of the die, with its gradual enlargement in width at the center and its rapid enlargement at the ends to form the side flanges 17 on the product. That is to say this second stage will bend the metal transversely in a vertical direction and also, as far as may be necessary, in a horizontal direction. In this second stage of the operation there is a slight drawing of the metal, but not enough to require the same power as where the product is made by drawing directly from a flat blank.

Before the operation the blank 8 rests on top of the die as shown in Fig. 1 and is held in place by small gages; but the clamp employed to hold the edges in the usual drawing operation is dispensed with and the metal is free to bend in the manner described. With this operation we can determine in advance the exact shape of the blank necessary to produce an article of the shape and dimensions desired and no trimming operation of the edges is necessary.

The product may be made curved in cross-section instead of substantially angular as shown, and may in fact be made of various shapes in longitudinal and in cross-section, and also in horizontal section. The invention is most obviously applicable to comparatively long narrow pieces of work and to the bending of the work lengthwise in the first stage, but the bending may be accomplished in either of two transverse directions first, and the process may be ap-

plied to work of various other proportions.

Though I have described with great particularity of detail a specific embodiment of my invention, yet it is not to be understood therefrom that the invention is restricted to the particular apparatus and process shown. Various modifications thereof in detail and in the arrangement of the parts may be made by those skilled in the art without departure from the invention as defined in the following claim.

What I claim is:—

An apparatus for producing from a sheet-metal blank a segment of a rear axle housing, comprising a die having sides 11 shaped on their upper edges 12 to the desired longitudinal contour of the segment and having a bottom 15 parallel to and shaped similarly to said edges, and a one-piece punch having a working face 14 similarly shaped arranged to co-operate with the sides of the die to bend the work to the contour of the upper edges of such sides, said punch having its working face of less width than the recess of the die so as to force the work, after it has been bent to the contour of the sides, down against the bottom of the die and to bend up the side portions of the work to a width determined by the contour of the edges of the sheet-metal blank from which the segment is formed.

In witness whereof, I have hereunto signed my name.

HENRY S. HOLMES.
